Primary Examiner — Shannon W Morgan(74) *Attorney, Agent, or Firm* — GTC Law Group PC & Affiliates(57) **CLAIM**

The ornamental design for a caddy, as shown and described.

DESCRIPTION

FIG. 1 is a front perspective view of a caddy showing the new design;

FIG. 2 is a right side elevation view thereof;

FIG. 3 is a left side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines and areas within depicted in FIG. 6 depict portions of the caddy that form no part of the claimed design.

1 Claim, 4 Drawing Sheets(56)
